UNITED STATES PATENT OFFICE.

CHARLES MAY, OF LONDON, ENGLAND.

APPARATUS FOR ASCERTAINING THE LEVEL OF LIQUIDS.

No. 820,429.

Specification of Letters Patent.

Patented May 15, 1906.

Application filed July 25, 1904. Serial No. 218,181.

To all whom it may concern:

Be it known that I, CHARLES MAY, electrician, a subject of the King of Great Britain, residing at 92 to 94 Paul street, Finsbury, 5 London, England, have invented certain new and useful Improvements in Apparatus for Ascertaining the Level of Liquids, of which the following is a specification.

This invention relates to apparatus for ascertaining the level of liquids, and is especially applicable for use on board ship to ascertain the level of water in the ballast-tanks and bilges.

In each tank or compartment are fixed a 15 number of contact-points at various heights, which may be a number of insulated rods descending to different levels. The contact-points are connected by wires to a switchboard, there being a switchboard for every 20 tank or compartment. Each switchboard is provided with a pivoted switch which is constructed to pass in rotation over the terminals of the wires. A lead from the pivoted switch is connected, through the secondary 25 winding of an induction-coil, to an indicator, either aural or visual, such as a telephone, and to earth. The primary winding of the induction-coil is connected to the two poles of a battery, and in the circuit is a key for 30 making or breaking the circuit. In place of or as well as the key is a mercury-level, which when there is any movement of the ship makes and breaks the circuit, the level being preferably arranged that the circuit is only 35 completed when the vessel is not at a greater angle than five degrees.

The drawing illustrates apparatus made in accordance with my invention.

'a is a tank containing liquid b, and a', a², 40 a³, and a⁴ are insulated rods descending to different levels in the tank. Similarly, c is the section of a ship containing liquid d in the bilge, and c', c², c³, and c⁴ are insulated rods descending to different levels in the bilge. 45 The rods a', a², a³, and a⁴ are connected to terminals e', e², e³, and e⁴ of a switchboard e, and a pivoted switch f is free to pass over the terminals, and the rods c', c², c³, and c⁴ are connected to terminals g', g², g³, and g⁴ of a 50 switchboard g, having a pivoted switch h.

The switches f and h are connected, through the secondary winding of an induction-coil k, to a telephone l to earth. The primary winding of the induction-coil is connected to 55 the two poles of a battery m, and in the circuit is a key n and a mercury-level o. In or-

der to prevent accidental leakages in the primary producing sounds in the telephone, a shunt p, having in it a resistance q, is provided.

To ascertain the depth of liquid, say in the tank a, the operator places the telephone l to his ear, taps the key n, and moves the switch f over the terminals. By tapping the key n a current is sent through the primary of the 60 induction-coil k; but no current passes through the secondary until the switch f makes contact with the terminal corresponding to the contact-point in the tank a which first comes into operation. The circuit is 65 then completed from one end of the secondary of the induction-coil to the contact in the tank, and so through liquid to earth, the other end of the secondary being also connected through the telephone to earth. This 70 current flowing through the secondary causes the diaphragm of the telephone to be attracted, thus making a click. The operator then knows the depth of liquid by observing which terminal the switch is in contact with. When a mercury-level is used, the 75 ship must be given time to roll before the switch is moved from one contact to the other. The switchboards may be placed in any convenient positions and any number 80 of them may be congregated together.

By using this apparatus no direct current is used in the tank-wires and no electrolytic action takes place in the tanks, which action has generally been the cause of failure of apparatus of this class for ascertaining the level 85 of liquids.

What I claim is—

1. Apparatus for ascertaining the level of liquids, consisting of a series of contacts at 90 different levels, a corresponding series of terminals, each connected to one of the contacts, a switch free to move over the terminals, an indicator and an induction-coil, to the secondary winding of which is connected the 95 switch and the indicator, the primary winding being in circuit with a source of electricity, and means for opening and closing the circuit.

2. Apparatus for ascertaining the level of liquids, consisting of a series of contacts at 100 different levels, a corresponding series of terminals, each connected to one of the contacts, a switch free to move over the terminals, an indicator and an induction-coil, to the secondary winding of which is connected the 105 switch and the indicator, the primary wind- 110

ing being in circuit with a source of electricity, a mercury-level in the primary circuit, and means for opening and closing the circuit.

3. Apparatus for ascertaining the level of liquids, consisting of a series of insulated rods of different lengths, a corresponding series of terminals, each connected to one of the rods, a switch free to move over the terminals, an indicator and an induction-coil, to the secondary winding of which is connected the switch and the indicator, the primary winding having in its circuit a source of electricity, means for opening and closing the circuit, a 30 shunt across the terminals of the induction-coil, and a resistance in the shunt.

4. Apparatus for ascertaining the level of liquids, consisting of a series of insulated rods of different lengths, a corresponding series of terminals, each connected to one of the rods, a switch free to move over the terminals, an indicator and an induction-coil, to the secondary winding of which is connected the switch and the indicator, the primary winding having in its circuit a source of electricity, a mercury-level, and means for opening and closing the circuit.

5. Apparatus for ascertaining the level of liquids, consisting of a series of contacts at

different levels, a corresponding series of terminals, each connected to one of the contacts, a switch free to move over the terminals, an indicator and an induction-coil, to the secondary winding of which is connected the switch and the indicator, the primary winding having in its circuit a source of electricity, means for opening and closing the circuit, a 35 shunt across the terminals of the induction-coil, and a resistance in the shunt.

6. Apparatus for ascertaining the level of liquids, consisting of a series of contacts at different levels, a corresponding series of terminals, each connected to one of the contacts, a switch free to move over the terminals, an indicator and an induction-coil, to the secondary winding of which is connected the switch and the indicator, the primary winding having in its circuit a source of electricity, a mercury-level, means for opening and closing the circuit, a shunt across the terminals of the induction-coil, and a resistance in the shunt.

CHARLES MAY.
